ATTORNEY

UNITED STATES PATENT OFFICE

ABRAHAM POLLAK, OF FAR ROCKAWAY, NEW YORK, AND JOSEPH F. O'BRIEN, OF ENGLEWOOD, NEW JERSEY, ASSIGNORS TO CLARK LIGHTER CO. INC., A CORPORATION OF MARYLAND

POCKET LIGHTER

Application filed January 28, 1928. Serial No. 250,112.

This invention relates to improvements in pocket lighters and more particularly to that type of lighter wherein a wick is ignited through manual rotation of a spark wheel in contact with a pyrophoric element.

One of the objects of this device is to produce a construction in which the sparking wheel will be readily removable for cleaning or renewal purposes and at the same time will, when mounted be fully guarded against contact with the thumb of the user during the wick-igniting operation thereof.

Another object is to improve, simplify and strengthen the construction of this type of lighter, and particularly to simplify and strengthen the construction and mounting of the sparking and operating mechanism thereof, and also to provide a lighter of neat, ornamental appearance, which may be produced at a low cost.

Still another object of this invention is to produce a construction which may be readily, quickly and easily assembled by unskilled labor and may be demounted for cleaning or renewal and reassembled by the user without the use of any tools.

Still another object of this invention is to provide a novel mounting of the sparking mechanism composed of a thumb wheel and a spark wheel so that when moved by the thumb of the user in one direction will cause a shower of sparks and ignition of the wick to be produced, while if the pyrophoric element is withdrawn and the thumb wheel rotated in the opposite direction while holding against rotation the spark wheel will cause a raising and demounting of the sparking element to enable the renewal thereof, if desired.

Another object of the invention is to provide a bearing for the shaft on which the ignition and operating wheels are mounted which will be supported at one end in the fuel reservoir; will be supported intermediate its ends in a bearing formed in a pan shaped guard and will have its opposite end unsupported and provided with a spark wheel above the said bearing.

Another object of the invention is to provide the spark wheel with an ornamental

cap which serves as a cover, and which with the guard almost completely encloses the spark wheel and enhances the ornamental appearance for the lighter.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a side elevation of a cigar lighter embodying our invention;

Fig. 2 is a plan view of the lighter shown in Fig. 1;

Fig. 3 is a section on the line 3—3 of Fig. 2, looking in the direction of the arrow, showing the sparking and thumb wheels in assembled relationship, the closing head for the wick tube being removed;

Fig. 4 is a view similar to Fig. 3, showing the spark and thumb wheels disassembled, while the cover tube is arranged in place over the wick;

Fig. 5 is a fragmentary section of the upper part of the lighter showing the novel means for mounting the wick-extinguishing head; and

Fig. 6 is a section on the line 6—6 of Fig. 1, looking in the direction of the arrow.

Referring now to these drawings, which illustrate a preferred embodiment of our invention, 1 indicates a reservoir which comprises the body of the device and is adapted to be held in the hand of the user. 1' indicates a base plate of said reservoir and 1^a indicates a top plate on which is mounted the flame-producing element and sparking mechanism, preferably in such compact relationship that the sparking mechanism may be operated by the thumb of the user, while the reservoir is held in his hand. The reservoir 1 is preferably provided with a suitable filler such as the cotton 2 and a suitable volatile liquid fuel is supplied to the reservoir to saturate the cotton 2. The fuel and cotton may be intro-

90

85

95

100

duced through an aperture in the base plate 1' which is capped by a suitable screw cap 1^b.

The reservoir 1 is provided with a wick tube 3 mounted perpendicular to and extending through the top plate 1^a of the casing and suitably secured therein, and a wick 4 extends through this tube and into contact with the fuel-saturated material in the reservoir, the upper end of said wick projecting beyond the upper end of the tube 3.

10 The upper end of this wick tube 3 is provided with a flange 3' and is opened and closed by a head 5 having a notch 6 of sufficient depth to fit over the upper end of the wick and to rest upon the flange 3' and thus to seal the wick tube and prevent evaporation of the volatile liquid fuel within the reservoir. As illustrated, the head 5 is mounted on a rearwardly-extending arm 7 pivoted at 15 its rear end on a pivot pin 8 extending perpendicular to the plate 1^a and, as shown, comprising a reduced portion of a projection 9 mounted on the end of the top plate opposite to the wick tube. The arm 7 is, as shown, 20 provided at its opposite end with a bore 7 having its lower end reduced as at 7^a to form an abutment for a spring 9', which is mounted on the reduced portion 8 and has an abutment at one end against a head of the screw 8 25 threaded into a tapped hole in said pivot pin and at the other end abuts against the reduced flange portion 7^a of the bore 7'. The effect of this arrangement is that the head 5 at the outer end of this arm will be permitted 30 to have a limited upward movement to free itself from the wick tube and, furthermore, will permit said arm to have an axial or lateral swinging movement about said perpendicular pivot. Because of the pressure of 35 the spring, this arm will be automatically retained in any position to which it is moved.

40 A pyrophoric tube 10 is supported intermediate its ends by a standard 11 mounted on and in perpendicular relationship to the top plate 1^a. Said pyrophoric tube is provided with a pyrophoric element 12, see Fig. 6, which is normally pressed in a forward direction by a spring 13 abutting at one end against a screw 14 threaded in one end of said tube and at the other end pressing against 45 said pyrophoric element 12. Said pyrophoric element is thus resiliently pressed forwardly into contact with a sparking wheel 15 which is made fast in any suitable manner on a perpendicular shaft 16 supported intermediate its ends, below the spark wheel 15 in a bearing 17 formed in a dish-shaped finger guard 18 provided at the forward end of the pyrophoric tube 10. The shaft 16 is provided with means for separable engagement 50 with and disengagement from a thumb wheel 20 arranged below said bearing, and is also preferably provided at its lower end with a reduced bearing portion 16' which is adapted 55 to extend within a bearing aperture 17' in the

70 top plate of the reservoir. As illustrated, the connection between the shaft 16 and the operating wheel 20 comprises cooperating left-hand threads, the shaft 16 being provided with an external left-hand screw thread 19 and the operating wheel being provided with an internal left-hand screw-threaded bore 20'.

75 In order to assemble, the operating wheel 20 is placed with its left-hand screw-threaded bore 20' beneath the bearing 17 and the threaded portion 19 of the shaft 16 is engaged therewith by a movement of the thumb wheel 20 toward the right until the said wheel 20 and shaft 16 are completely locked together, it being understood that the bearing portion 16' will extend through the bearing 17'. When the screw-threaded portion is passed 80 through the bearing and into engagement with the screw-thread bore 20' of the operating wheel 20, a rotation or turning of the 85 wheel 20 to the left, while the shaft 16 with its sparking wheel 15 is held against rotation, will cause the shaft to be moved downwardly and the parts may be speedily assembled. When the parts have reached the position in 90 which the bearing collar 16^a engages the top of the wheel 20, the parts may be thus assembled by a movement of the wheel in the same direction that is required for causing a sparking 95 operation. This is the easiest method of assembly.

100 Of course, if desired, the wheel 20 may be retained against rotation and the shaft 16 therein by a movement in a reverse direction. In either case, when it is desired to demount the sparking wheel, all that is necessary to do is to hold the shaft against rotation by manual engagement of the cap of the 105 sparking wheel 15 which is fast thereon and at the same time rotate the operating wheel in the reverse direction from that in which it is normally operated to produce a spark. When the operating wheel is so rotated, the shaft will be caused to rise and the parts may thus be readily disassembled.

110 In the preferred embodiment of our invention, we provide on the top of the spark wheel 15 a cap 15' which is preferably formed of ornamental metal and when the spark wheel and operating wheel is connected as hereinabove described this cap, together with the dish-shaped finger-guard member will provide a substantially complete covering with ornamental material of the sparking wheel at all points except that through which 115 the shower of sparks are caused to pass.

120 In operation, the lighter may be held in the hand of the user, the head 5 may be removed from the wick by the thumb and thereafter movement by the thumb of the operating wheel in the direction of the arrow shown in Fig. 2 will cause a shower of incandescent particles or sparks from the pyrophoric element to be projected against the wick which, when saturated with the fuel, as 125 130

hereinabove described, will be ignited to produce a light for a cigar or the like. The light or flame may be extinguished by again moving the head 5 into contact with the wick tube.

Having described our invention, we claim:—

1. A lighter embodying in combination, a fuel reservoir having a top mounting plate, a wick tube extending perpendicular of said mounting plate, a tube mounted away from but parallel to said top mounting plate, and carrying therein a piece of pyrophoric material, sparking mechanism arranged at the end of said tube, which comprises a sparking wheel and a thumb-operating wheel separable from each other and having intermediate thereof a bearing portion adapted to seat in an intermediate bearing formed on one end of said tube and away from the top mounting plate and comprising an extension of the end of the tube formed to provide a dish-shaped member, serving as a finger guard around the sparking wheel.

2. The structure recited in claim 1, characterized in that both the sparking wheel and the thumb wheel are allocated so that both wheels are disposed above and away from the top mounting plate.

3. A lighter embodying in combination, a fuel reservoir having a top plate, a wick tube extending perpendicular of said top plate and ignition mechanism comprising a tube mounted away from but parallel to said top mounting plate and carrying therein a piece of pyrophoric material, and sparking mechanism arranged at the end of said tube comprising a sparking wheel, and a thumb-operating wheel, separable from each other, but threadedly and operatively connected together and having intermediate said wheels a bearing portion adapted to seat in an intermediate bearing formed on one end of the tube away from said top mounting plate and carrying an extension of the lower end of the tube formed to provide a dish-shaped member serving as a finger guard around the sparking wheel, and said wheel being provided with an ornamental cap atop thereof.

4. A lighter embodying in combination, a fuel reservoir having a top plate, a wick tube extending perpendicular of said top plate, an ignition mechanism comprising a tube mounted away from but parallel to said top mounting plate having a piece of pyrophoric material mounted therein, and sparking mechanism arranged at the end of said tube comprising a sparking wheel and a thumb-operating wheel, separable from each other, and having a bearing portion intermediate the same, adapted to sit in an intermediate bearing formed on one end of the tube and away from the top mounting plate and carrying an extension of the outer end of the tube formed to provide a dish-shaped meni-

ber serving as a finger guard around the sparking wheel, said wheel being provided with an ornamental cap atop thereof, said connection between said two separable parts of the sparking mechanism being formed by providing said parts with cooperating screw-threads adapted to tighten the parts together by a movement of the thumb wheel in the same direction as the operating movement and to cause the separation thereof by a movement of said wheel in the opposite direction while holding the sparking wheel against rotation.

5. The structure recited in claim 4, characterized in that both the sparking wheel and the thumb wheel are allocated, so that both wheels are disposed above and away from the top mounting plate.

6. A lighter embodying, in combination, a fuel reservoir having a top mounting plate, a wick tube extending perpendicular of said mounting plate, a second tube mounted away from but parallel to said top mounting plate and having mounted therein a piece of pyrophoric material, sparking mechanism arranged at the end of said tube comprising a sparking wheel and a thumb wheel, separably mounted and operatively and threadedly connected together, a supporting bearing formed on one end of said tube and engaging said sparking mechanism between said thumb wheel and said sparking wheel and a flame extinguishing sealing rigid member mounted on said mounting plate comprising a head having a wick extinguishing and sealing notch at one end and pivoted on a pivot at the other end arranged perpendicular to the top plate and the connection between said arm and pivot having sufficient loose motion to permit of raising of said rigid member a limited distance above the wick and a swinging of the same on said perpendicular pivot.

7. A rigid wick snuffer arm for use in a lighter consisting of a sealing member mounted on the mounting plate of the lighter and which comprises a head having a wick-flame extinguishing and sealing notch at one end, and a pivot on the other end of said rigid arm which pivot is arranged perpendicular to said top plate and is resiliently connected to said rigid arm, so as to leave sufficient loose motion to permit of the raising of said rigid arm, a limited distance above the wick and swinging of the same on said perpendicular pivot.

8. A lighter embodying, in combination, a fuel reservoir having a mounting plate, a wick extending perpendicular to said mounting plate, a tube mounted away from but parallel to said top mounting plate having a piece of pyrophoric material mounted therein, sparking mechanism arranged at the end of said tube comprising a sparking wheel and a thumb wheel separably mounted and operatively connected together, a supporting bear-

- ing formed on one end of said tube and engaging said sparking mechanism between said thumb wheel and said sparking wheel, a flame extinguishing and wick tube sealing member mounted on said mounting plate comprising a head having a wick extinguishing and sealing notch at one end and pivoted at the other end on a pivot arranged perpendicular to the top plate, the connection between said arm and pivot having sufficient loose motion to permit raising of the rigid arm a limited distance above the wick and a swinging of the same on said perpendicular pivot and a spiral spring having a bearing at one end at the opposite end bearing against an abutment on the arm so as to normally retain the head in a lowered position and also to retain it at any swung-out position to which it may be moved.
9. A wick snuffer arm for use in a lighter having a top mounting plate consisting of a flame extinguishing and wick tube sealing member mounted on said mounting plate, comprising a head having a wick extinguishing and sealing notch at one end and pivoted at the other end of said rigid arm on a pivot arranged perpendicular to said top plate, and having a resilient connection between said rigid arm and pivot, which has sufficient loose motion to permit of the raising of said rigid arm a limited distance between the wick and swinging out of the same on said perpendicular pivot.
10. A rigid wick-snuffer arm structure for use in a lighter consisting in a standard mounted atop the top plate of the lighter, a pivot secured to said standard, a rigid arm bored at one end to sit on and be secured to said pivot, resilient means securing said arm to said pivot to permit of raising and swinging of said rigid arm thereabout, and a head, located at the outer end of said rigid arm, having a wick-flame extinguishing sealing notch thereon.
11. A rigid wick-snuffer arm structure for use in a lighter having a top plate consisting in a rigid arm having enlargements at both ends thereof one of said enlargements having a wick-flame extinguishing sealing notch thereon and the other of said enlargements being bored to provide a hole therethrough.
12. A rigid wick-snuffer arm structure for use in a lighter having a top plate consisting in a rigid arm having enlargements at both ends thereof one of said enlargements having a wick-flame extinguishing sealing notch thereon and the other of said enlargements being bored to provide a hole therethrough having a reduced portion, a standard mounted atop the top plate, a pivot adapted to be secured to said standard and resilient means seating within said hole, about said pivot and against said reduced portion for securing the arm to the pivot so as to permit of raising and swinging it thereabout.

13. A rigid wick-snuffer arm structure for use in a lighter having a top plate consisting in a rigid arm having a wick-flame sealing notch at one end thereof and an enlargement at the other end thereof, a pivot and means for resiliently securing said rigid arm to said pivot so that said arm is universally movable thereabout, said resilient means being disposed within a bored portion on said enlarged end.

14. A lighter embodying in combination, a fuel reservoir having a top mounting plate, a wick tube extending perpendicular of said mounting plate, a tube mounted away from but parallel to said top mounting plate and having a piece of pyrophoric material disposed therein, sparking mechanism arranged at the end of said tube comprising a sparking wheel having an abrader surface, a rounded completely smooth ornamental end, a circular flat end and a reduced shafting portion, a thumb wheel separably mounted and operatively connected thereto, a single supporting bearing formed on one end of said tube adapted to operatively hold said sparking mechanism at said reduced portion by engaging it between the said thumb and sparking wheels, and said sparking mechanism also having a bearing in the mounting plate adapted to receive the extension of said shafting.

15. An abrader wheel for use in a cigar lighter having a flat bearing surface, an ornamental completely smooth rounded top end, a cylindrical abrader surface, and reduced means adapted to rotatably support such abrader wheel in contact with an element to be abraded.

In witness whereof, we have signed our names to the foregoing specification.

JOSEPH F. O'BRIEN.
ABRAHAM POLLAK.
